UNITED STATES PATENT OFFICE.

PIETER C. DE GROOT, OF ROTTERDAM, NETHERLANDS, ASSIGNOR TO U. S. SLICING MACHINE COMPANY, OF CHICAGO, ILLINOIS, A CORPORATION OF ILLINOIS.

SHARPENING DEVICE FOR SLICING-MACHINE KNIVES.

1,168,379.

Specification of Letters Patent. Patented Jan. 18, 1916.

Application filed January 2, 1914. Serial No. 309,825.

To all whom it may concern:

Be it known that I, PIETER C. DE GROOT, a subject of the ruler of the Netherlands, residing at Rotterdam, in the Kingdom of the Netherlands, have invented certain new and useful Improvements in Sharpening Devices for Slicing-Machine Knives, of which the following is a specification.

This invention relates to improvements in sharpening device for slicing machine knives preferably of the rotary circular type, and one of the objects of the same is to provide an improved device of this type by means of which the knife may be readily and efficiently sharpened, and which device when not in use may be moved into a position out of the way.

A further object is to provide an improved device of this character, embodying a sharpening device for the face of the knife, having means whereby the device may be always maintained in a substantially parallel position with respect to the face of the knife.

To the attainment of these ends and the accomplishment of other new and useful objects as will appear, the invention consists in the features of novelty, in substantially the construction, combination and arrangement of the several parts, hereinafter more fully described, and claimed and shown in the accompanying drawings exemplifying the invention, and in which:

Figure 1 is a front elevation of an improved device of this character constructed in accordance with the principles of this invention, and showing the same in an operating or grinding position. Fig. 2 is a sectional view taken on line 2—2, Fig. 1. Fig. 3 is a sectional view taken on line 3—3, Fig. 2. Fig. 4 is a detail top plan view of the sharpener for one face of the knife showing the same in two positions. Fig. 5 is a sectional view on line 5—5, Fig. 1. Fig. 6 is a view of the parts shown in Fig. 1, showing the sharpening device in an inoperative position and moved back out of the way. Fig. 7 is a top plan view of the parts shown in Fig. 6. Fig. 8 is a sectional view as taken on line 8—8, Fig. 9. Fig. 9 is a top plan view similar to Fig. 7 of a modified form of the invention. Fig. 10 is a view similar to Fig. 4 of a modified form of the invention. Fig. 11 is a detail sectional view on line 11—11, Fig. 8.

Referring more particularly to the draw-

ings and in the present exemplification of this invention, the numeral 15 designates a rotary cutter journaled in the usual support 16 and being provided with a substantially flat and a bevel face as is customary with cutters of this character. In the form of the invention shown in Figs. 1 to 7, there is provided an upright designated generally by the reference numeral 17, which is removably secured to the support 16 in any suitable manner preferably by having one of its extremities 18 threaded into the slide 19, the latter being adjustably secured to move the support toward and away from the lateral face of the cutter by suitable fastening devices 20.

Surrounding the upright 17 adjacent its lower end is an elastic member 21, preferably in the form of a coil spring which is housed within a sleeve 22, the end 23 of the sleeve being provided with a threaded aperture, adjacent the element 19, and in which aperture the extremity 18 of the upright 17 is threaded. The sleeve may be of any desired length, but terminates preferably adjacent the longitudinal center of the upright, and a sleeve 24 loosely contacts the upper portion of the upright and is provided with a closed extremity having an aperture therethrough and through which the aperture the reduced extremity 25 of the upright 17 loosely passes. This sleeve 24 is connected with the upright 17 preferably by means of a pin or bolt, which passes through the sleeve, with its extremity entering a spirally arranged groove 27 in the upright, and which extends lengthwise of the upright, so that when the sleeve 24 is moved longitudinally of the upright, it will also be given a rotary or pivotal movement about the upright. The sleeve 24 is of a length, that the extremity of the elastic member 21 will engage against the lower extremity thereof and a cam device 28, is pivotally connected as at 29, with the extremity of the reduced portion 25 of the upright. This cam device is provided with a handle 30 by means of which it may be swung about its pivot to cause the cam device to engage a plate or cap 31 to depress the sleeve 24 against the stress of the elastic member 21, or to be moved about its pivot in the opposite direction to permit the stress of the elastic member to raise the sleeve 24. Anti-friction devices 32 may be provided between 110

the plate 31 and the end of the sleeve 24 to reduce friction. In order to limit the extent of depression of the sleeve 24 and consequently limit the downward movement of 5 the sharpening device, which latter will be hereinafter described, the lower extremity of the sleeve 24 may be threaded as at 33 to receive a nut 34, which is adapted to abut the extremity of the sleeve 22, and a jam 10 nut 35 may also be provided for holding the nut 34 in position. Obviously by adjusting these nuts 34, 35, the extent of the reciprocating movement of the sleeve 24 may be varied. A housing 36 may also be provided, 15 if desired, for the nuts 34, 35, and the pin 26, and which housing may be removably secured to the sleeve by one or more fastening devices 37.

A collar 38 is supported by the sleeve 24 20 to move therewith and this collar is provided with arms or brackets 39, 40, (see particularly Figs. 6 and 7). A bearing 41 is provided in the arm or bracket 39 and in which bearing a spindle 42 is journaled, the 25 bearing having connected therewith a grinding or sharpening device 46 adapted to act on the bevel face 47 of the cutter 15. An elastic member 48 is housed within the bearing with one extremity engaging a support 49, and the other extremity engages a 30 collar or shoulder 50 connected with the spindle. A handle 51 is provided which contacts with the shoulder 49 and is adapted to move the spindle longitudinally in the 35 bearing against the stress of the elastic member and thereby regulate or control the degree of pressure against the cutter.

A grinder 52 provided with a substantially flat face 53 is provided for the other 40 side of the cutter, and is connected with a spindle 54 mounted in a bearing 55 and which bearing is pivotally connected as at 56 with the arm or bracket 40. An elastic member 57 is housed within the bearing 55 45 and abuts a shoulder 58, through which the spindle slides, and this shoulder 58 abuts a stop 59 fixed with respect to the bearing. The other end of the elastic member abuts a shoulder or collar 60 which is connected 50 with the spindle 54. The grinder 52 in its operating position is arranged on the side of the knife opposite to the side on which the grinder 45 is arranged, and in order to permit the grinder 45 to operate and to 55 render the grinder 52 inactive, a handle 61 is provided which has a portion adapted to contact with the shoulder 60, so that when pressure is exerted upon the handle, the spindle 54 will be moved longitudinally in 60 its bearing against the stress of the elastic member, to move and hold the grinder 52 into the dotted line position in Fig. 5, and out of contact with the face of the knife. Obviously when the handle 61 is released, 65 the elastic member will move the grinder

52 into contact with the face of the knife as shown in the full line position in Fig. 5.

By the provision of the pivot 56, the bearing 55 will move about a substantially upright pivot, and this pivotal movement 70 will permit the face of the grinder 52 to be automatically maintained in a substantially parallel position with respect to the face of the knife. The pivotal movement of the bearing may be limited by means of suitable 75 stops 62, 63 (see Fig. 7), and guards 64 may be provided if desired for the grinders.

The operation of this improved construction briefly stated is as follows: Assuming the parts to be in operating position as 80 shown in Fig. 1, that is with one of the grinders on each side of the knife, and in contact with the respective faces thereof. The grinding operation will be effected by the rotation of the grinders, and which motion will be imparted thereto by the rotation of the knife. If it is desired to grind the bevel face and not the other face of the knife, all that is necessary is to press upon the handle 61 of the grinder 52 to hold this 90 grinder out of contact with its face of the knife, until it is desired to bring it into operation. To accomplish this the handle 61 is simply released. After the grinding has been completed all that is necessary is 95 to swing the cam device 28 about its pivot and from the position shown in Fig. 1. This will release the position of the support which carries the grinders, and permit it to be moved by the stress of the elastic member 21 upon the upright 17, to raise the 100 grinders. During this raising movement, the pin and spiral grooves 26, 27 will impart a pivotal or rotary movement to the sleeve 24, and also the grinders, to move them 105 away from the cutter, by shifting one of the grinders across the edge of the knife into the position shown in Fig. 6, or until both of the grinders are on one side of the knife. From this position, and when it is again 110 desired to sharpen the knife, all that is necessary is to depress or swing the cam device 28 in opposite direction about its pivot 29. This will depress the sleeve 24 against the stress of the elastic member 21, and as 115 the sleeve is descending upon the upright 17 it will be given a rotary or pivotal movement to swing one of the grinders across the edge of the knife, and both grinders in operating position, or until they contact with 120 the respective faces of the knife, it being understood that the downward movement of the sleeve 24 is limited in this form of the invention, by the engagement of the nut 34 with the end of the sleeve 22.

In the form of the invention shown in Figs. 8 to 10, the sleeve 65 which corresponds with the sleeve 24 is of a length to extend for some distance along the upright 17 and is provided with a housing 66 in which a 125 130

portion of the elastic member 21 extends, so that one extremity thereof abuts a shoulder 67 in the housing, while the other extremity of the elastic member abuts a nut or collar 68 mounted upon the threaded extremity 18 of the upright. The lower extremity of the sleeve 65 is provided with external threads 69 to receive the nut 70, which latter is adapted to abut the nut 68 to limit the downward movement of the sleeve 65, and a jam nut 71 may be provided for holding the nut 70 in its adjusted position with respect to the sleeve 65. Obviously the degree of movement of the sleeve 65 may be varied by adjusting either the nut 60 or 70, or both. In this form of the invention, a single bracket 72 is provided on the sleeve and which bracket has arms 73, 74 carrying the sharpening devices 45, 52. The bearing 55 of the sharpener 52 is pivotally connected as at 75 with the arm 74, and a portion of the arm 74 projects between spaced stops 76 and is adapted to engage one or the other of these stops for limiting the pivotal movement of the grinder 52. The operation of this form of the invention is similar to the form shown in Figs. 1 and 2.

While in the present exemplification of this invention, the preferred forms and constructions have been herein shown and described, it is to be understood that various changes may be made, in the details of constructions, and in the combination and arrangement of the several parts, without departing from the spirit of this invention, and it is therefore to be understood that the drawings are to be considered as being merely diagrammatic.

What is claimed as new is:—

1. A sharpening device of the character described, embodying a sharpener for acting on each face of the knife, a freely shiftable support carrying both sharpeners, said sharpeners being fixed with respect to each other, and provisions for shifting the support to simultaneously move the sharpeners into active positions with relation to the respective faces of the knife.

2. A sharpening device of the character described, embodying a sharpener for acting on each face of the knife, a support carrying both sharpeners, said sharpeners being fixed with respect to each other, provisions for imparting a compound movement to the support to simultaneously move the sharpeners into active positions with relation to the respective faces of the knife, and provisions for moving the sharpeners in directions toward each other.

3. A sharpening device of the character described, embodying a sharpener for the front of the knife, a sharpener for the back of the knife, a support for both sharpeners, said sharpeners being fixed with respect to each other, means for shifting the support

to move the sharpeners into and out of active position with relation to the respective faces of the knife, and means for imparting another and different movement to the support during a portion of the said shifting movement.

4. A sharpening device of the character described, embodying a sharpener for the front of the knife, a sharpener for the back of the knife, a support for both sharpeners, said sharpeners being fixed with respect to each other, means for shifting the support to move the sharpeners into and out of active position with relation to the respective faces of the knife, and means for automatically imparting another and different movement to the support during a portion of the said shifting movement of the support, to move one of the sharpeners over the edge of the knife.

5. A sharpening device of the character described, embodying a sharpener for the front of the knife, a sharpener for the back of the knife, a support carrying both the sharpeners, provisions for imparting a compound movement to the support to simultaneously move the sharpeners into active positions with relation to the respective faces of the knife, and means for acting on each of the sharpeners for yieldingly holding them in engagement with the faces of the knife.

6. A sharpening device of the character described, embodying a shiftable support, a sharpener for the face of the knife, a sharpener for the back of the knife, said sharpeners carried by the support and fixed with relation to each other, provisions for shifting the support to simultaneously move the sharpeners into and out of active positions with respect to the knife, and provisions operating automatically to cause both sharpeners to assume a position on one side of the knife.

7. A sharpening device of the character described, embodying a shiftable support, a sharpener for the face of the knife, a sharpener for the back of the knife, said sharpeners carried by the support and fixed with relation to each other, provisions for shifting the support to simultaneously move the sharpeners into and out of active positions with respect to the knife, and provisions whereby another and different movement will be imparted to the support during a portion of its shifting movement for causing both sharpeners to assume a position on the same side of the knife.

8. A sharpening device of the character described, embodying a shiftable support, a sharpener for the face of the knife, a sharpener for the back of the knife, said sharpeners carried by the support and fixed with relation to each other, provisions for shifting the support to simultaneously move the

sharpeners into and out of active positions with respect to the knife, and provisions for imparting another and swinging movement to the support during its shifting movement.

9. A sharpening device of the character described, embodying a sharpener for the front of the knife, a sharpener for the back of the knife, and a pivoted support carrying both sharpeners, said sharpeners being fixed with respect to each other, and adapted to be simultaneously brought into operative relation with the respective faces of the knife by the pivoted movement of the support.

10. A sharpening device of the character described, embodying a sharpener for the front of the knife, a sharpener for the back of the knife, and a support having a compound movement and carrying both sharpeners, said sharpeners being fixed with relation to each other and adapted to be brought into operative positions with relation to the respective faces of the knife, by the compound movement of the support, said sharpeners maintaining their fixed relation during the movement of the support.

11. A sharpening device of the character described, embodying a sharpener for the front of the knife, a sharpener for the back of the knife, a support carrying both sharpeners, said sharpeners being fixed with relation to each other, provisions for imparting to the support a compound movement to simultaneously move the sharpeners in directions toward and away from the knife into and out of their planes of operation.

12. A sharpening device of the character described, embodying a sharpener for the front of the knife, a sharpener for the back of the knife, a support carrying both sharpeners, provisions for shifting the support to move the sharpeners toward and away from the knife, and provisions for imparting a rotary movement to the support during its shifting movement.

13. A sharpening device of the character described, embodying a sharpener for the front of the knife, a sharpener for the back of the knife, a freely shiftable support carrying both sharpeners, provisions for shifting the support to move the sharpeners toward and away from the knife, and yielding means acting upon each of the sharpeners for holding them yieldingly in contact with the faces of the knife.

14. A sharpening device of the character described, embodying a sharpener for the front of the knife, a sharpener for the back of the knife, a freely movable support carrying both of the sharpeners, provisions whereby a movement of the support will cause the sharpeners to be simultaneously brought into engagement with the respective faces of the knife, and provisions whereby one of the sharpeners may be maintained

out of engagement with its face of the knife during such movement of the support.

15. A sharpening device of the character described, embodying a sharpener for the front of the knife, a sharpener for the back of the knife, a movable support carrying both of the sharpeners, provisions whereby a movement of the support will cause the sharpeners to be simultaneously brought into engagement with the respective faces of the knife, and provisions whereby the face of one of the sharpeners may be automatically maintained in substantially parallel relation with the respective face of the knife.

16. A sharpening device of the character described, embodying a sharpener for the front of the knife, a sharpener for the back of the knife, means supporting the sharpeners, and provisions for automatically maintaining the active face of one sharpener substantially parallel with the respective face of the knife.

17. A sharpening device of the character described, embodying a sharpener for the front of the knife, a sharpener for the back of the knife, means supporting the sharpeners, and means connecting one of the sharpeners with its support for movement about an upright pivot.

18. A sharpening device of the character described, embodying a sharpener for the front of the knife, a sharpener for the back of the knife, means supporting the sharpeners, provisions for automatically maintaining the active face of one sharpener, substantially parallel with the respective face of the knife, and yielding means acting upon each sharpener for yieldingly holding the sharpeners in engagement with the respective faces of the knife.

19. A sharpening device of the character described, embodying a sharpener for the front of the knife, a sharpener for the back of the knife, means supporting the sharpeners, provisions freely pivoting one of the sharpeners for automatically maintaining the active face of such sharpener in substantially parallel position with relation to the respective face of the knife, and means for limiting such pivotal movement of the sharpener in one direction.

20. A sharpening device of the character described, embodying a sharpener for the front of the knife, a sharpener for the back of the knife, means supporting the sharpeners, provisions freely pivoting one of the sharpeners for automatically maintaining the active face of such sharpener in substantially parallel position with relation to the respective face of the knife, and spaced stops for limiting such pivotal movement of the sharpener.

21. A sharpening device of the character described, embodying a support, sharpeners carried thereby, one of said sharpeners

adapted to act on each side of the knife, means tending normally to raise the support, and provisions for imparting a rotary movement to the support during the raising 5 and lowering movements thereof.

22. A sharpening device of the character described, embodying a support, sharpeners carried thereby, one of said sharpeners adapted to act on each side of the knife, 10 means tending normally to raise the support, and provisions for causing a compound movement of the support during the raising and lowering movements thereof, and operating to shift one of the sharpeners across 15 the knife.

23. A sharpening device of the character described, embodying a support, sharpeners carried thereby, one of said sharpeners adapted to act on each side of the knife, 20 means tending normally to raise the support, and provisions for imparting a rotary movement to the support during the raising and lowering movements thereof, the said rotary movement of the support operating 25 to shift one of the sharpeners from one side to the other side of the knife.

24. A sharpening device of the character described, embodying a support, sharpeners for opposite sides of the knife carried there- 30 by, yielding means tending normally to move the support in one direction, provi- sions for moving the support in the opposite direction and against the stress of the said yielding means, and provisions for impart- 35 ing another and different movement to the support during portions of its first recited movements to swing the sharpeners to one side of the knife.

25. A sharpening device of the character 40 described, embodying a support, sharpeners for opposite sides of the knife carried there-

by, yielding means tending normally to move the support in one direction, provi- sions for moving the support in the oppo- 45 site direction and against the stress of the said yielding means, provisions for impart- ing another and different movement to the support during portions of its first recited movements to swing the sharpeners to one side of the knife, and provisions for varying 50 the extent of the first recited movements of the support.

26. A sharpening device of the character described, embodying a support, sharpeners for opposite sides of the knife carried there- 55 by, yielding means tending normally to move the support in one direction, provi- sions for moving the support in the oppo- site direction and against the stress of the 60 said yielding means, and provisions for im- parting another and different movement to the support during portions of its first recited movements to swing the sharpeners to one side of the knife, the said provisions em- 65 bodying a pin and a spirally arranged groove receiving the pin.

27. A sharpening device of the character described, embodying a sharpener for the front of the knife, a sharpener for the back of the knife, said sharpeners being fixed 70 with relation to each other, and provisions controlling both of the sharpeners whereby the sharpeners may be simultaneously moved into and out of engagement with the respective faces of the knife and while the 75 sharpeners are maintained in their fixed re- lation.

In testimony whereof I have signed my name to this specification, in the presence of two subscribing witnesses, on this 15th day 80 of December, A. D. 1913.

PIETER C. DE GROOT.
